UNITED STATES PATENT OFFICE.

WILLIAM E. GARD, OF BROOKLYN, NEW YORK.

CRANK.

SPECIFICATION forming part of Letters Patent No. 542,885, dated July 16, 1895.

Application filed March 5, 1895. Serial No. 540,634. (No model.)

To all whom it may concern:

Be it known that I, WILLIAM E. GARD, a citizen of the United States, residing at Brooklyn, in the county of Kings and State of New York, 5 have invented certain new and useful Improvements in Cranks; and I do hereby declare the following to be a full, clear, and exact description of the invention, such as will enable others skilled in the art to which it appertains to make and use the same.

My invention relates to cranks, and particularly to cranks for bicycles or other similar vehicles; and my invention consists in the novel construction of the crank, in the novel 15 means employed for holding the parts of the crank together, in the novel means employed for permitting access to the crank-bearings, and in the novel form, construction, and arrangement of the parts constituting my 20 proved crank.

The objects of my invention are, first, to provide a crank having as few parts as possible, which shall be light and of simple construction, easily taken apart and put together, 25 and which shall not be liable to come apart unintentionally; second, to provide a crank so constructed as to permit of easy access to the bearings and to permit one crank-section to be removed without disturbing the other 30 crank-section; third, to provide simple means for interlocking the ends of the crank-shaft sections and for fastening the two parts of the crank together, and to so arrange the crank-bearings that pressure upon the crank-bearings, 35 due to pressure upon the pedals, may cause the sections of the crank-shaft to be pressed together, thereby removing strain from the device which primarily holds the shaft-sections together, reducing the danger 40 of breakage of this device, and enabling the bicycle to be used, even though this device, which primarily holds the shaft-sections together, is broken, and, fourth, to make the crank strong, durable, and as inexpensive as 45 possible. These objects are attained in the crank herein described, and illustrated in the drawings which accompany and form a part of this application, in which the same reference-numerals indicate the same or corresponding parts, and in which—

Figure 1 is a longitudinal section of the crank-bearings and crank-bracket of a bicy-

cle, showing my improved bicycle-crank. Fig. 2 is a similar view showing modifications thereof and in particular a modified method 55 of securing the crank-bearing cones in place, and also means for stiffening the joint between the two crank-sections, so as to resist tendency toward flexure at the joint. Fig. 3 is an end view of one of the sections of the 60 crank-shaft shown in Fig. 2, showing particularly the slots in which the flat keys are placed; and Fig. 4 illustrates another method for stiffening the joint between the crank-sections against flexure. 65

In the drawings, 1 is an ordinary bottom or crank-bracket formed upon the lower portion of the frame of the bicycle, which receives the crank-shaft and crank-bearings.

2 and 2' are the crank-arms, which are secured to or formed integrally with the crank-shaft sections 3 and 3', which together form the crank-shaft. The ends of these sections 3 and 3' are formed with projecting tongues or tenons 4 and 4', separated by corresponding grooves or mortises, which are so formed that the tongues of one section of the crank-shaft fit into the grooves of the other section, the two sections of the crank-shaft being thereby interlocked, so that one must turn 80 with the other.

Various forms of corresponding and interlocking tongues and grooves may be used, and I do not limit myself to any particular form; but if the ends of the sections of the 85 shaft be formed as shown in the drawings they may be made exactly alike, and if in other respects the two parts of the crank are alike these parts may both be made from one and the same pattern. 9c

The two sections of the crank-shaft are held together and are prevented from separating longitudinally by a screw or key 5, passing through the crank-shaft from one side to the other, and accessible through an aperture 6 95 in the bracket 1, through which a screw-driver may be inserted for turning the screw in and out. This aperture may be provided with a suitable cover to prevent the entrance of dust.

Directly upon the sections of the crank-shaft are placed cones 7 and 7' for the ball bearings in which the crank-shaft runs, and into the ends of the bracket 1 are screwed corresponding cones 8 and 8'. Between the 100

cones 7 and 8 and 7' and 8' are placed the balls 9.

In the form of crank shown in Fig. 1 shaft-sections 3 and 3' are provided with shoulders 5 10 and 10', slightly larger in diameter than the main portion of the shaft and screw-threaded, and the cones 7 and 7' are arranged to screw upon these shoulders 10 and 10' and against the ends of shoulders 11 and 11', 10 which are slightly larger in diameter than the shoulders 10 and 10', and which determine the positions of these cones, therefore. If necessary lock-nuts may be used to prevent the cones from moving backward; but in general 15 this will be unnecessary, as the direction of rotation of the crank is such as to tend to cause the cones to press more and more tightly against the shoulders 11 and 11'.

In the form of crank shown in Fig. 2 the 20 cones 7 and 7' are shown as secured in place by keys or by brazing. They may be secured to the shaft-sections in any other suitable way, or may be formed integral with the shaft-sections.

25 Upon the crank-shaft section 3' is carried the sprocket-wheel 13, which may be secured in place in any ordinary and common manner, as by keys, set-screws, or by shrinking it in place. In the construction shown in Fig. 30 1 the sprocket-wheel 13 rests upon the shoulder 11' and is put in place before the cones 8 and 7 are put on. In the construction shown in Fig. 2, since the cones 7 and 7' are fixed in place permanently, it is impossible 35 to pass the sprocket-wheel and cones 8 and 8' over these cones 7 and 7' unless the sprocket-wheel and the cones 8 and 8' be made excessively large, and I have made the crank-arms with a more gradual curve, so that the cones 40 and the sprocket-wheel may be put in place by passing them over the crank-arms.

It will be noted that the cones 7 and 8 and 7' and 8' are so placed with reference to each other that the pressure of the bearing-surfaces tends to press the sections of the crank together, and therefore takes from the screw 5 a large portion of the strain that might otherwise come upon it should there be any tendency of the crank-sections to separate longitudinally. The screw 5, therefore, may be made much smaller than would otherwise be advisable. This arrangement of the cones likewise has the additional advantage that if through any accident the screw 5 should break, the sections of the crank-shaft will not come apart and the bicycle may still be used, the only result, if any, being a slightly-greater friction at the crank-bearings and a slightly-greater danger of wear at those bearings.

60 To give rigidity to the joint between the shafts 3 and 3' and to enable it to resist any possible tendency toward flexure at the joint it may be advisable to use two or more screws 5, placed longitudinally a short distance from each other. The same result may be accomplished in another way. (Shown in Figs. 2 and 3.) Each shaft-section is provided with a

thin slit 15 running longitudinally and in line with the center of the screw-hole through which the screw 5 passes. This slit is slightly 70 wider upon the side without the screw-hole than it is upon the side within the screw-hole. A thin plate or key 16 is inserted in the slit in each shaft-section, the width of this key being such that when driven to the bottom of 75 the slit it will come to or nearly to the edge of the screw-hole. This plate is of such thickness as to make a drive fit with the lower or inner portion of the slot, which is slightly narrower than the upper or outer portion, 80 while it merely makes a close fit with the corresponding slit in the other crank-shaft section, within which it lies when the two shaft-sections are together. These two plates then constitute a practically continuous key, which 85 greatly stiffens the joint and prevents any possible bending. The same result may also be accomplished in the manner shown in Fig. 4 by inclosing the sections of the crank-shaft in a closely-fitting sleeve 17 of considerable 90 length. In this sleeve, opposite the ends of the screw 5, are holes through which this screw may be removed; and to prevent the sleeve from turning with respect to the crank-shaft, as well as to prevent the sleeve from covering 95 the ends of the screw 5 and so preventing access thereto the length of the screw 5 should preferably be slightly greater than the diameter of the crank-shaft.

In Fig. 2 the ends of the crank-shaft sections are shown enlarged to strengthen them at the joint.

In assembling the parts of the crank and crank-bearings above described, if the construction be that of Fig. 1, the sprocket-wheel 105 13 is slipped over the end of the section 3', seated upon the shoulder 11', and is secured in place. The cone 8' is then put upon the section 3', which it fits loosely, and after it the cone 7', which is screwed upon the shoulder 10' until it rests against the end of the shoulder 11'. If the sprocket-wheel is too close to the cones 7' and 8' to permit the balls 9 to be put in place between these cones after the cone 7' is in place they may be placed between the cones before the cone 7' is quite in place, and the cone 7' may then be screwed down into place. The cones 7 and 8 are then placed upon the section 3 in a similar manner, the balls 9 being placed between them. The two sections of the crank-shaft are then placed within the bracket 1 and pressed together, the tongues of the one section fitting into the grooves of the other. When they have thus engaged and have been pushed as 115 near together as is possible with the cones 8 and 8' unscrewed, these cones are screwed into the ends of the bracket 1, thus forcing the two parts of the crank together. The screw 5 is then inserted through the hole 6 in the 120 bracket and is screwed home, thus securing the parts together finally.

In assembling the sections of the crank,

when constructed as shown in Fig. 2, the operation is in general the same, except that in this case, since the cones 7 and 7' are rigid upon the sections 3 and 3', the cones 8 and 8' and the sprocket-wheel must be put in place by passing them over the ends of the crank-arms 2 and 2' before the crank-treadles are attached.

If the flat keys 16 are used to stiffen the joint between the crank-sections, they are driven each into the slot in its respective shaft end before the cones are put on and thereafter stay in place. When the two ends of the crank-shafts are put together, each key slips into the slot in the end of the other shaft-section. If the sleeve 17 is used to stiffen the joint, it is put upon one shaft-section after the cones are in place thereon, and is slipped into the crank-bracket with the shaft-section. The end of the other shaft-section is then inserted into this sleeve and the parts are attached as before, the screw 5 being passed through the holes in the side of the sleeve and into the screw-hole in the crank-shaft.

As shown in Figs. 1 and 2, the lengths of the shaft-sections 3 and 3' are exactly the same, as the two parts of the crank are designed to be interchangeable, and as the section 3 of the crank-shaft has no sprocket-wheel 13 upon it, it follows that it is comparatively easy to gain access to the bearing on that side of the crank by simply unscrewing the cone 8; but if, as is usually the case, the "tread" of the machine is made as narrow as possible, so that the crank-arm 2' and sprocket-wheel 13 fit closely to the cone 8', there is not sufficient room to remove the cone 8' in order to obtain access to the bearing upon its side of the crank. Access to this bearing may be gained by removing the screw 5 and then drawing out the section 3' of the crank-shaft, at the same time unscrewing the cone 8', and this may be done without in the least disturbing the bearing upon the other side of the crank.

It will often happen that it is more important to have as great a distance as practicable between the crank-bearings than it is to have the two parts of the crank interchangeable. Where such is the case the length of the bracket 1 will be such that the cone 8 is very close to the crank-arm 2; but in this case access to the bearing may be obtained in the same manner as to the bearing upon the sprocket side of the crank and without in the least disturbing the bearing on that side and the sprocket-wheel.

My invention is not limited in its application to bicycles and similar vehicles, but may be applied to other machinery driven by cranks. Neither is it limited to ball-bearings, but may be used with other types of bearings—as, for instance, the ordinary conical bearings.

Having thus completely described my invention, what I claim, and desire to secure by Letters Patent, is—

1. In a crank, the combination, with two crank arms, and two crank shaft sections, secured each to one of said crank arms, and having ends adapted to interlock, of independent bearing cones mounted upon said crank shaft sections, and facing toward the crank arms, and other bearing cones, suitably supported and adapted to engage with said shaft cones, and facing toward the center of the crank-shaft, substantially as described. 70

2. In a crank, the combination, with two crank arms, and two crank shaft sections, secured each to one of said crank arms, and having ends adapted to interlock, of independent bearing cones mounted upon said crank shaft sections, and facing toward the crank arms, other bearing cones, suitably supported and adapted to engage with said shaft cones, and facing toward the center of the crank shaft, 80 and a key, passing through the interlocking ends of said shaft sections and adapted to hold the same together, substantially as described. 85

3. In a crank, the combination, with two crank arms, and two crank shaft sections, secured each to one of said crank arms, and having mortised and tenoned ends adapted to interlock, of independent bearing cones mounted upon said crank shaft sections, and facing 90 toward the crank arms, other bearing cones, suitably supported and adapted to engage with said shaft cones, and facing toward the center of the crank shaft, and a screw passing through the interlocking ends of said shaft sections and adapted to hold the same together, substantially as described. 95

4. In a crank, the combination, with two crank arms, and two crank shaft sections, secured each to one of said crank arms, and having ends adapted to interlock, of independent bearing cones mounted upon said crank shaft sections, and facing toward the crank arms, other bearing cones, suitably supported and adapted to engage with said shaft cones, and facing toward the center of the crank shaft, 105 and means for stiffening the joint between said crank shaft sections at said joint and preventing flexure thereat, substantially as described. 110

5. In a crank, the combination, with two crank arms, and two crank shaft sections, secured each to one of said crank arms, having ends adapted to interlock, and having in said ends longitudinal and registering slots adapted to receive keys, of bearing cones mounted upon said crank shaft sections, other bearing cones suitably supported and adapted to engage with said shaft cones, flat keys, lying within the slots in the ends of said shaft sections, and arranged to stiffen the joint between said shaft sections and prevent flexure thereat, and a key, passing through the interlocking ends of said shaft sections and holding the same together, substantially as described. 125

6. The herein described crank, consisting

of two separable crank sections, each consisting of a crank arm having secured rigidly thereto or formed integrally therewith a section of the crank shaft, the ends of said crank-
5 shaft sections being adapted to interlock and being provided with an equal number of corresponding and registering mortises and ten-
ons, whereby both of said crank sections may be made alike, and means for holding said

crank sections together, substantially as de- 10
scribed.

In testimony whereof I affix my signature in presence of two witnesses.
